UNITED STATES PATENT OFFICE.

JAMES LYNAN, OF NEWBURGH, NEW YORK, ASSIGNOR TO E. I. DU PONT DE NEMOURS POWDER COMPANY, OF WILMINGTON, DELAWARE, A CORPORATION OF NEW JERSEY.

AUTOMATIC PRESS-FEEDER.

1,091,855.

Specification of Letters Patent. Patented Mar. 31, 1914.

Application filed December 21, 1911. Serial No. 667,238.

To all whom it may concern:

Be it known that I, JAMES LYNAN, a citizen of the United States, residing at Newburgh, county of Orange, and State of New York, have invented a new and useful Improvement in Automatic Press-Feeders, of which the following is a full, clear, and exact description, reference being had to the accompanying drawings, which form a part 10 of this specification.

My invention is particularly adapted for use where a paper or fabric strip is carried beneath a press for the purpose of printing or embossing.

Specifically it has for its purpose to provide means to produce what may be called, a step by step movement to cause the paper, fabric, or composite paper and fabric to feed under a press, to dwell during the pressing and then to be moved forward.

It is also my purpose to provide such a device which is capable of taking care of sheets of different widths.

I will now describe the embodiment of my invention shown in the accompanying drawings and then point out the invention in the claims.

In the drawings: Figure 1 is a side elevation partially in section of a machine embodying my invention. Fig. 2 is a partial plan view of the same. Figs. 3, 4 and 5 are detail views of my improved gripping device.

a is the roll or drum upon which the 35 fabric or paper to be treated is placed, and *b* is the roll to which it is ultimately delivered. The roll *a*, by means of clamps *c* is so held as to require a pull to unwind the paper. The winding roll *b* is driven by means, which 40 will hereinafter be described, but the driving is such that it is insufficient to pull the paper or fabric from the original roll *a* but is sufficient to keep it taut.

d is a press which, for example, may be an 45 embossing press. As, so far, described, the paper or fabric on the carrying roll *a* may there be unwound sufficiently to carry it through the press and on to the winding roll *b*, whose action, as before described, is sufficient 50 to maintain the sheet taut but insufficient to pull it from the winding roll. On the other hand, if desired, a fabric may be attached to the winding roll *b* of sufficient length to extend back through the press, and

to which the fabric or paper to be treated 55 may be attached.

My invention, as before described, relates specifically to a device whose purpose is to pull the fabric or paper or material to be embossed through the press with a step by 60 step movement. This I accomplish as follows: *e*—*e* are standards on opposite sides of the machine. Each standard at its lower end is attached to a shoe *f* which is guided in a groove *g* in the bed of the machine. The 65 upper end of each standard is attached to a link *h* which in turn is attached to the crank *i*, which crank *i* is on the shaft *j*. This shaft *j* carries the bevel wheel meshing with the bevel wheel *l* on the shaft *m*. On the lower 70 end of the shaft *m* is a bevel wheel *n*, meshing with the bevel wheel *o* on the driving shaft *p*. On the shaft *j* is the pulley or belt wheel *q* on which is a belt *r* which passes to a pulley or belt wheel *s* connected to the 75 roller *b*. When the shaft *j* is revolved, the standards *e* are given a reciprocating movement. Between these two standards *e* and extending across the machine, is a cross bar *t*. Mounted upon this cross bar *t* are gripper frames *w*. These gripper frames *w* are 80 slidable on the bar *t* and are secured thereto at the desired transverse position by means of the bolts *u*.

The gripper proper consists of the pivoted 85 bevel ended dog *v* it being pivoted to the gripper frame *w* so as to, normally, hang vertically, the depending beveled edges contacting with the base of frame *w*, when there is no fabric present. This prevents 90 movement of the dog *v* to the left, Fig. 4, but allows it to swing to the right. There is also provided a stop *x* which acts as a counterweight to bring the dog back to the vertical position after it has been swung to the 95 right, and also by contacting with the frame acts to stop the dog being swung too far to the right. The construction of this gripping dog *v* is such that in one movement of the standards *e* and its frame *w*, to wit: the 100 forward movement, it will move from the paper or fabric without gripping, but in the reverse or return direction it will grip the paper or fabric, pulling it forward the distance equal to the length of movement of 105 frame *w*. It should have been stated that the frame *w* is outside the paper or fabric strip and the dog *v* overhangs inwardly, so

that the free travel of the paper or strip to be treated by the press is in no way affected.

In practice the forward and rearward movement of the standards *e* are such as to 5 pull the desired amount of the paper or fabric to be treated in alinement with the press, and a small amount away from the press, and in the return movement of the gripper it remains in that position for a length of 10 time sufficient for the press to act. By this construction, with certainty, the fabric or paper *y*, to be treated in the press, is in proper lengths brought under the action of the press, retained there a sufficient period 15 for the press to act, and during the free movement of the press is withdrawn and a new portion brought into place.

Further, it may be seen that this device is equally applicable with varying widths of 20 fabric or paper, because the gripper frame may be moved along the rods or beams to accommodate the width of the paper or material being acted upon, and all without in any way affecting the free movement of the 25 paper. When this gripping device or press feeder pulls the proper amount forward and releases it, it creates a slack which the roller *b* in its rotation is able to take up and winds upon that roll. The arrangement, however, 30 is such that if there were no slack, the roller *b* would be unable to pull the fabric or paper forward on account of the slippage of the belt which drives that roller.

Having now fully described my invention, 35 what I claim and desire to protect by Letters Patent is:

1. In an apparatus of the character described, a pair of longitudinally reciprocable and laterally adjustable gripping frames 40 each comprising a base and a bracket whose lower end is supported at a distance from the inner edge of the base, said bracket having an upper overhanging portion, and a gripping dog pivoted on and depending from the 45 overhanging portion of each bracket and offset inwardly relatively to the supported lower end of the bracket and overhanging the part of the base inside the supported lower end of the bracket.

50 2. In an apparatus of the character described, in combination, a transversely adjustable gripping frame having a base over the inner part of which the part of the fabric or paper adjacent to its longitudinal edge 55 is adapted to slide, means to reciprocate said frame longitudinally, said frame having an upwardly and longitudinally extending bracket located toward the outer part of the base, and a gripping dog pivoted on the 60 bracket and overhanging a part of the gripping frame base inside the bracket.

3. In an apparatus of the character described, in combination, a gripper frame having an overhanging portion, means to reciprocate the frame, a gripping dog pivoted on and freely depending from said overhanging portion, said dog adapted to swing toward the fabric in a direction opposite to that of the feed in position to grip the fabric during the feeding movement of the frame 70 but being of such length as not to swing beyond the gripping position, said dog tending, when the frame is moved in the opposite direction, to swing away from the fabric in the direction of feed, and means adapted to 75 limit the swing of the dog in the last named direction and tending to return the dog to its gripping position.

4. In an apparatus of the character described, a pair of longitudinally reciprocable 80 and laterally adjustable gripping frames, each frame comprising a base and an overhanging bracket projecting upward from the base at a distance from the latter's inner edge whereby the frame may be adjusted to 85 bring the inner portion of its base under the fabric or paper to be fed, a gripping dog normally depending vertically from the overhanging bracket, part of which dog overhangs the inner portion of the base and part 90 of which overhangs a portion of the base outside said inner portion, said dog having a lower end beveled downward in a forward direction, thereby enabling it to feed only 95 in its forward direction of movement.

5. In an apparatus of the character described, in combination, a gripping frame, an overhanging pivoted gripping dog, the lower surface of the dog having a bevel face and means to reciprocate said frame, and a 100 regulating device connected to said dog acting in one direction of pivotal movement of the dog as a stop and in the other direction as a counterweight.

6. In an apparatus of the character described, in combination, gripping frames, each frame having a pivoted overhanging dog, the lower surface of which has a bevel face, said frames being movable toward and 105 from each other and means to reciprocate said frames in unison, a regulating device connected to each dog acting in one direction of pivotal movement of its corresponding dog as a stop and in the other direction as a counter weight.

In testimony of which invention, I have hereunto set my hand, at Newburgh, N. Y., on this 14th day of December, 1911.

JAMES LYNAH.
